UNITED STATES PATENT OFFICE

2,503,344

CORN HUSKING ROLLER

Austin R. Martin, Warsaw, Mo.

Application October 7, 1946, Serial No. 701,830

3 Claims. (Cl. 130—5)

1

This invention relates to corn husking rollers.

An object of this invention is to provide a husking roller having husk removing fingers which are so constructed and mounted that they will remove the husks without removing the kernels of corn from the cob.

Another object of this invention is to provide a husking roller with resilient husking fingers which project from the cylindrical wall of the roller. In one form of this invention each finger is formed integral with an end of a resilient bar which is fixedly secured to the inside of the roller. In a second form of this invention, the finger is formed with a spiral base which is slidable through the wall of the roller, and a spring bearing against the inner side of the base constantly urges the finger outwardly.

A further object of this invention is to provide an improved mounting for one member of each pair of rollers, the mounting including a swingable spring-pressed bearing at each end of one roller so as to thereby prevent crushing of the ears of corn and also to provide resilient gripping contact between the pairs of rollers to pull the loosened husks from the cobs.

With the above and other objects in view, my invention consists in the arrangement, combination and details of construction disclosed in the drawings and specification, and then more particularly pointed out in the appended claims.

In the drawings,

Figure 1 is a detail side elevation of a series of corn husking rollers constructed according to an embodiment of this invention.

Figure 2 is a fragmentary plan view of a pair of the rollers,

Figure 3 is a fragmentary sectional view taken on the line 3—3 of Figure 2,

Figure 4 is a fragmentary transverse sectional view taken on the line 4—4 of Figure 2,

Figure 5 is a fragmentary sectional view taken substantially on the line 5—5 of Figure 4.

Figure 6 is a fragmentary side elevation of the yieldable mounting for one member of each pair of rollers.

Figure 7 is a fragmentary sectional view of a modified form of roller construction,

Figure 8 is a sectional view taken on the line 8—8 of Figure 7.

Referring to the drawings, and first to Figures 1 to 5 inclusive, the numeral 10 designates generally a frame which is formed of opposite parallel side members 11. The frame 10 has journaled between the side members 11 thereof pairs of husking rollers 12 and 13. The rollers 13 are

5 mounted in fixed bearings 14 which are secured to the side members 11 whereas the rollers 12 are mounted in swinging bearings as will be hereinafter described. The rollers 12 and 13 are of like construction and the detailed description of one of these rollers will apply equally as well to the other roller.

The roller 12 includes a cylindrical body 15 which has secured to the opposite ends thereof 10 head members 16. The head members 16 have disposed in the axial center thereof outwardly extending stub shafts 17 having a plate 18 at their inner ends secured by fastening means 19 or the like to the head 16. The roller 12 has the 15 stub shaft 17 at one end thereof journaled through a bearing sleeve 20 which is carried by a vertically disposed supporting plate 21. The supporting plate 21 is pivotally secured to a base member 22 which is secured by fastening means 20 23 to the upper side of a side member 11.

The bearing member 20 has an eye 24 extending angularly and downwardly therefrom with which one end of a roller tensioning spring 25 is adapted to engage. The opposite end of the 25 spring 25 is secured to an eye 26 of a turn buckle 27. The opposite end of the turn buckle 27 which has an eye 28 is secured by fastening means 29 to the outer side of the side member 11. The turn buckle 27 extends downwardly from the roller 12 and in the direction of the roller 13 so that the tensioning of the spring 25 will cause the roller 12 to be spring tensioned against the roller 13. The roller 12 has extending therethrough, a plurality of husking fingers 30 which loosely extend through countersunk openings 31 formed in the cylindrical body 15. The husking fingers 30 are disposed in staggered relation about the periphery of the roller 12 and the free end of each finger 30 is slightly expanded and formed as an 35 encircling stop means to avoid any tendency of the finger end to catch in the openings 31 and formed integral with the inner end thereof is a resilient bar 32 or body section placed at 90° thereto and extended longitudinally of the drum 40 terminating in an eye 33 formed integrally thereof.

A fastening bolt or screw 34 is extended through the body 15 from the outer side thereof and then extended through the eye 33. A clamping nut 35 is threaded on the inner end of the bolt 34 and a washer 36 may be interposed between the nut 35 and the adjacent side of the ring 33. When the finger 30 strikes the adjacent outer surface of the roller 13, the finger 30 is pressed inwardly as shown in Figure 5. The length of

each finger bar 32 or body section is relatively long, being proportioned to effect a gentle pressed finger action against the unhusked ears of corn just sufficient for penetration of the husk without injury to or the shelling of the corn kernels from the cob.

These fingers 30 are designed to separate the husks from the corn cob so that the spring tensioned rollers will grasp the free ends of the husk and pull the husk from the cob as the rollers rotate. The roller 12 has mounted on at least one stub shaft thereof, a sprocket 37 and the roller 13 has mounted on its associated stub shaft a sprocket 38. A roller operating chain 39 engages the sprockets 37 and 38, being trained over the top of the sprocket 37 and beneath the sprocket 38. In this manner the two rollers forming a pair, will rotate in opposite direction. The chain 39 is trained over a driving sprocket 40 carried by a driving shaft 41 which is connected to a suitable power means and preferably the upper run 42 of the chain 39 is trained over an idler sprocket 43.

According to the preferred form of the invention, the stationary rollers 13 rotate in a counter-clockwise direction while the so-called floating rollers 12 rotate in a clockwise direction. The removed husks will inevitably drop downwardly through the spaces shown between the adjacent pairs of rollers while at the same time these spaces are not sufficiently large to permit the ears to drop.

As will be appreciated, the rotation of the rollers will automatically carry the ears forwardly from the driving end to the driven end, or in fact, such rotating rollers may automatically result in the shucked ears being moved laterally of the apparatus and off the same. If desired, to facilitate this more or less gravitational sliding movement of the corn-ears away from the rollers, the latter may be inclined slightly to one side or the other.

Referring now to Figures 7 and 8, there is disclosed a modified form of roller construction and husking finger. The body 44 of the roller has extending inwardly therefrom a cylindrical member 45 which is formed with a closed inner end 46. The cylindrical member 45 is internally threaded as at 47 and a nut 48 engages the threads 47. A movable or spring finger 49 is slidable through the bore 50 of the nut 48 and is formed at its inner end with a spiral base 51. The base 51 bears against the inner end of the nut 48 and the diameter of the base 51 is such as to provide for the free inward movement of the finger 49 and the base 51. A finger tensioning spring 52 is interposed between the inner side of the base 51 and the bottom wall 46 and a washer 53 is interposed between the outer end of the spring 52 and the inner side of the base 51.

With a husking roller construction as hereinbefore described, the husk loosening finger or the finger 49 will loosen the husks from the corn cob without loosening the kernels of corn and the loosened husks will be grasped between the contacting portion of the two rollers 12 and 13 which will thereupon pull the loosened husk from the corn cob or ear. The tension of the fingers 30 and 49, is such as to provide the necessary loosening action of the husk without loosening or removing the kernels of corn from the ear. In any of the resilient fingers become damaged they can be readily replaced by the insertion of a new finger as will be readily apparent. The insertion of the new finger is made for the construction shown in Figures 1 to 5 by removing one of the

end heads and then inserting the finger into the interior of the roller and applying the head bolt to the eye of the finger construction. The spring pressed or resilient finger shown in Figure 7 can be readily replaced by unthreading the tensioning nut 48 and inserting a new finger for the damaged one.

I do not mean to confine myself to the exact details of construction herein disclosed, but claim all variations falling within the purview of the appended claims.

What I claim is:

1. In a corn-husking apparatus a frame, a pair of substantially parallel horizontally extending cylindrical drums rotatably supported by said frame, a plurality of depressible prong-like members having ends extending outwardly from the peripheral surfaces of said drums said prong-like members having an elongated body section formed at 90° angles thereto and extending longitudinally of and within its supporting drum with a secured end oppositely spaced from the prong end and formed as a loop for fixed engagement to said drum, the said prong-like members of one of said drums being staggered with respect to those of the other drum, one of said drums being supported in relatively stationary bearings provided in said frame and the other of said drums being supported in relatively movable bearings of said frame, driving means adapted for bringing about rotative movement of said drums, and means whereby there is permitted intermittent periods of spaced relationship and bearing engagement between said peripheral surfaces of said drums as the same are rotated, all adapted and arranged whereby when the drums are in surface-bearing engagement, the prong-like members are depressed and when the drums are in spaced relationship the prong-like members are released to operative positions.

2. In a corn-husking apparatus, a frame, at least a pair of substantially parallel horizontally extending cylindrical drums rotatably supported by said frame, each of said drums being provided with a plurality of apertures in its peripheral surface, a plurality of husk-engaging members each of which consists of a unitary length of rod-like resilient material and including an elongated body section extending longitudinally of and within its supporting drum forming resilient arms having their inner end portions formed as loops fastened on the inside of said drums and outer end portions bent at 90° angles thereto extendable outwardly substantially at right angles to said arms and normally projecting through said apertures in the drums at right angles to the longitudinal axis of said drums, and means whereby there is permitted intermittent periods of spaced relationship and bearing engagement between said peripheral surfaces of said drums as the same are rotated, all adapted and arranged whereby when the drums are in surface-bearing engagement, the prong-like members are depressed and when the drums are in spaced relationship the prong-like members are released to operative positions.

3. In a corn-husking apparatus, a frame, at least a pair of substantially parallel horizontally extending cylindrical drums rotatably supported by said frame, each of said drums being provided with a plurality of countersunk apertures in its peripheral surface, a plurality of husk-engaging members consisting of a unitary length of rod-like resilient material and including elongated resilient arms extending longitudinally of and

within their supporting drum having their inner end portions fastened on the inside of said drums and outer end portions bent at a 90° angle relative to each of said arms to form prong-like members extending outwardly substantially at right angles to said arms and normally projecting through said apertures in the drums at right angles to the longitudinal axis of said drums said prong-like members being depressible to recede into said drum with stop means formed at the end of each member to restrict its recession to flush positioning relative to the surface of the supporting drum, and means whereby there is permitted intermittent periods of spaced relationship and bearing engagement between said peripheral surfaces of said drums as the same are rotated, all adapted and arranged whereby when the drums are in surface-bearing engagement, the prong-like members are depressed and when the drums are in spaced relationship the prong-like members are released to operative positions,

the said apertures of one of said drums being in staggered relation with respect to those of the other drum.
